CAR-DOOR MECHANISM

Application filed October 7, 1927. Serial No. 224,579.

My invention relates to car door mechanism for retaining in closed position a hinged door which is adapted to swing to open position under the influence of gravity to permit 5 the lading of a car to be discharged. A principal object of the invention is to provide, in conjunction with suitable door locking mechanism, strong, simple and efficient means for forcing the door to closed position.

A principal feature of my invention consists in providing, in combination with a hinged door adapted to swing transversely of the car to open position under the influence of gravity, a plurality of members carried by the door and extending beyond an edge thereof, hooks cooperable with the members for maintaining the door in closed position, and means associated with the said hooks affording a plurality of fulcrum points for a removable lever thereby enabling the application of a prying force to the door adjacent each of the hooks.

Another feature of the invention resides 25 in combining with a pivoted dump car door having its hinge axis disposed longitudinally of the car, a plurality of devices spaced along the edge of the door remote from its hinge axis for supporting it in closed position, each 30 of said devices involving an arm secured to the door, a pivoted hook carried by a stationary part of the car, and a bracket overlying the outer face of the hook, and means rigid with said bracket constituting a fulcrum for 35 a removable lever for prying the door to closed position.

A further feature of the invention consists 40 in providing, in combination with a car having a floor and a side sill extending below said floor, a hinged door, and a plurality of means for supporting said door in closed position, each of said means involving an arm secured to the door and projecting outwardly beyond the side sill, a hook pivotally 45 mounted on the side sill, and a bracket overlying the outer face of said hook, a portion of said bracket depending below the side sill and being provided with means for accommodating a removable lever, the latter being 50 adapted to pry the door to closed position.

Other features and advantageous arrangements and combinations of parts will herein-after appear and be pointed out in the claims.

In the drawings, Figure 1 is a side elevational view of a portion of a railway car 55 showing my invention as applied thereto.

Figure 2 is a fragmentary detail sectional view taken on the line 2-2, Fig. 1.

Figure 3 is a view similar to Fig. 1, but showing a modified form of supporting 60 hook.

Figure 4 is a sectional view similar to Fig. 2, showing the relation of the door to the center sill of the car.

The railway car chosen for the purpose of 65 illustrating the invention is of the well known flat-bottom gondola type involving a side wall 1, floor 2, and side sill 3, the latter extending below the general level of the floor and constituting a continuation of the side 70 wall. The floor 2 is provided with an opening to permit the discharge of lading from the car, the opening being normally closed by a door 4 which may advantageously be provided with straps 23 for receiving hinge 75 pintles 24. As is usual in this type of car, the hinge pintles are disposed longitudinally of the car adjacent and substantially parallel to the center sill 25 so as to enable the door to swing transversely of the car to open position 80 under the influence of gravity. In the present instance the hinge pintles are shown as being carried by brackets 26 rigidly mounted on the center sill. Secured to the floor by bolts 5 and arranged to overlap the 85 edge of the door when the latter is in closed position, is a sealing strip 6 for preventing the loss of fine or granular lading.

A plurality of spaced arms or stiffeners 7 are attached to the under side of the door 4, 90 preferably by bolts 8, so as to extend beyond the edge of the door remote from its hinge axis, each of the arms being preferably disposed normal to the said hinge axis and to the car side. The outer ends 9 of the door 95 arms project underneath the side sill and terminate at a point outwardly thereof, the said ends being offset from and connected to the major portion of their respective door arms by inclined portions 10.

Pivoted secured to the outer face of the side sill are a plurality of gravity actuated hooks or shouldered members 11 adapted to respectively engage with the outer projecting ends of the door arms to support and maintain the door in closed position. Each of the hooks illustrated in Fig. 1 is provided with two ledges or shoulders 12 and 13, the former for cooperating with the door arm to support the door in a partial or preliminary position of closure, and the latter for cooperating with the arm to support the door in a full or final position of closure.

Overlying the outer face of each of the hooks and rigidly secured to the side sill, preferably by rivets 14, is a bracket 15. A pivoted cam 16 is interposed between the side sill and each of the brackets 15 for engagement with the hook to lock the latter in door supporting position. Each of the hooks and cams is pivotally supported by pivot rivets or posts 17 and 18, respectively which extend through the brackets 15 and sill 3.

As is well known, it is often very difficult to effect a complete closure of these swinging dump doors. This is due to the fact that the doors become warped and distorted because of the service to which they are subjected and, moreover, small pieces of lading sometimes lodge in positions making complete closure of the doors a matter of considerable difficulty. It is, however, in all cases an easy matter to swing the door to a partially closed position such as it would occupy when supported upon the preliminary ledges 12 of the pivoted hooks. To effect a complete closure of the door from this position it is necessary to afford efficient means whereby additional force may be employed for moving the door. For this purpose each of the brackets 15 is preferably integrally provided with an arm 19 depending below the side sill adjacent the pivoted hook and offset outwardly from the adjacent face of the side sill. The lower end of each of these arms is fashioned, as at 20, to afford a fulcrum for a removable lever 21 which is adapted to engage with a portion of the door, such as the outer end 9 of the door arm, whereby, when the lever is actuated, the door is caused to move to fully closed position.

It will be observed that by providing fulcrums on the brackets adjacent each of the pivoted hooks, a prying force may be applied to the door at the most advantageous points, and that by permitting the inner end of the lever to seat against the outer ends 9 of the door arms a particularly desirable result is accomplished, in that, should the ends of the door arms be accidentally bent or displaced downwardly out of their usual positions so that after the door has been moved to fully closed position the hooks

will not properly engage the door arms, the lever will, in its normal operation, force the door arms back into a position enabling the latter to be engaged by the hooks.

The fulcrum brackets 15 may be used practically as efficiently with a one step hook, as indicated at 22 in Fig. 3, as with the two step hook shown in Fig. 1. In many instances it will be found that the door has become warped or distorted in a manner such that when the door is raised by hand to closed position one side of the door will assume a position permitting the hook on that side to fully engage the adjacent door arm. In such a case it will be seen that the lever and fulcrum may be utilized to force the other side of the door into fully closed position. If, on the other hand, the door is warped to such an extent that neither of the single step hooks will supportingly engage the door arms, the lever may be employed to sustain the door in a position corresponding to partially closed position, from which position the lever will, upon being actuated, force the door to fully closed position as heretofore explained.

I claim:

1. In a door device for railway cars, the combination with a hinged door movable to open position under the influence of gravity, of a plurality of arms carried by the door, the outer end of each of said arms being offset downwardly from the door and projecting outwardly beyond the edge thereof remote from its hinge axis, independently movable hooks carried by a stationary part of the car for respectively cooperating with said arms to support the door in closed position, and a plurality of means spaced longitudinally of the car for cooperating with a removable lever for forcing the door to closed position, each of said means involving a bracket carried by a stationary part of the car and the outwardly projecting end of one of said door arms, each of said brackets overlying the outer face of the associated hook and being provided with means constituting a pivotal support for the hook.

2. In a railway car, the combination with a pivoted dump door having its hinge axis disposed longitudinally of the car, of a plurality of arms secured to the door and projecting outwardly beyond the car side, a plurality of independently pivoted hooks respectively cooperable with said arms to maintain the door in closed position, and brackets associated with each of said hooks having portions depending below the lower edge of the side of the car and outwardly of the outer ends of said arms, each of said portions being fashioned to receive a removable lever whereby a prying force may be applied to the outer end of the door arm adjacent each of said hooks.

3. In a door mechanism for railway cars,

the combination with a pivoted door having its hinge axis disposed longitudinally of the car, of a plurality of spaced arms secured to the door and projecting outwardly beyond the edge thereof remote from the hinge axis, the projecting ends of said arms being spaced below the door, independently operable hooks carried by a stationary part of the car for respectively cooperating with said arms to maintain the door in closed position, and means carried by the car adjacent the end of each of said arms for receiving a removable lever adapted to cooperate with the projecting ends of said arms to force them into position to be engaged by their associated hooks.

4. In a door mechanism for railway cars, the combination with a pivoted door having its hinge axis disposed longitudinally of the car, of a plurality of devices spaced along the edge of the door remote from its hinge axis for supporting it in closed position, each of said devices involving an arm secured to the door, a pivoted hook carried by a stationary part of the car, and a bracket overlying the outer face of said hook and having means constituting a pivotal support therefor, and means rigid with said bracket constituting a fulcrum for a removable lever for prying the arm into position to be engaged by the hook, said rigid means located outwardly of the end of said arm and disposed below the latter when the door is in closed position.

5. In a door mechanism for railway cars, the combination with a hinged door, of a plurality of devices spaced longitudinally of the car for maintaining the door in closed position, each of said devices involving an arm carried by the door and projecting beyond the adjacent side of the car, a gravity actuated pivoted hook mounted on a stationary part of the car and engageable with said arm, and a bracket overlying the outer face of the hook, said bracket having an offset portion provided adjacent its lower end with a ledge affording a fulcrum for a removable lever for forcing the door to closed position.

6. In a door device for railway cars, the combination with a car having a floor, and a side sill extending below said floor, of a hinged door, and a plurality of means for supporting said door in closed position, each of said means involving an arm secured to the door having an offset end projecting outwardly beyond the side sill, a hook pivotally mounted on the side sill, and a bracket overlying the outer face of the said hook, a portion of said bracket depending below the offset end of said arm when the door is closed and being provided with means for accommodating a removable lever, the latter being adapted to bear against the offset end of the door arm to pry the door to closed position.

7. In a door device for railway cars, the combination with a car having a floor and a side sill extending below said floor, of a hinged

door in said floor, an arm secured to said door and projecting beyond the side of the car beneath the side sill, a hook pivotally mounted on the side sill for engagement with the said arm to support the door in closed position, a bracket secured to said sill in overlapping relation to the outer face of the said hook, and means integral with said bracket constituting a fulcrum for a removable lever, said means being located outwardly of the outer end of the door arm and being arranged to permit the lever to engage with the latter and operate in a plane substantially normal to the car side to force the door to closed position.

8. In a railway car having a side and center sill and provided with a floor disposed above the lower edge of the said side sill, the combination with a door hinged in the floor, the hinge axis of the door being adjacent the center sill and extending longitudinally of the car, of a plurality of stiffening members secured to the under face of the door substantially normal to the hinge axis of the latter and the car side, the said members projecting beyond the free edge of the door, the outer end of each of said members being offset from the door and passing beneath the side sill outwardly beyond the car side, a plurality of door supporting members carried by the side sill for respectively cooperating with said stiffening members to maintain the door in closed position, and a fulcrum arranged near each of said supporting members adapted to receive a pry bar whereby said stiffening members may be forced upwardly one at a time to be engaged by said supporting members to maintain the door in fully closed position, the lever being supported by each of said fulcrums in substantial alinement with the offset end of the corresponding door arm.

In testimony whereof I affix my signature.
